UNITED STATES PATENT OFFICE

ELIJAH CHETWYND, OF TRENTON, NEW JERSEY.

DESIGN FOR DINNER-WARE.

SPECIFICATION forming part of Design No. 12,449, dated September 6, 1881.

Application filed July 11, 1881. Term of patent 7 years.

To all whom it may concern:

Be it known that I, ELIJAH CHETWYND, of Trenton, in the county of Mercer and State of New Jersey, have invented and produced a new and original Design for Dinner-Ware, of which the following is a specification.

In the accompanying drawings, Figure 1 is a perspective view of a covered dish made according to my new design. Fig. 2 is a plan view of the same.

The cover A is oval, and has a ledge, B, and a shoulder, B', above it, along its edge. The vessel or body C of the dish has a straight collar or band, D, at its upper edge, and from the lower edge of this band the body of the vessel is swelled outward, and is then contracted on a gently-curved line, which at the base passes abruptly into a concave line of the base E, provided with a bead, F.

20 The handles consist of two short longitudinally-fluted rods, G, inclined toward each other, and having their upper ends connected by a like fluted rod, the ends of these rods being surrounded by leaf ornamentation H.

25 A leaf ornamentation or palmetto ornamentation, J, is arranged on the lid or on the dish, where the same and the ends of the rods G are united. The space between the inclined rods is filled in with a plate, K, with a recess 30 or depression, L, in its upper edge, which recess forms the aperture of the handle.

The above-described design is not only to be used for covered dishes, but for soup-tureens,

sauce-tureens, casseroles, and other dinner-ware in general.

These dishes are to be made of porcelain, &c.

I claim—

1. The herein-described design for a cover for a dinner-dish, the same consisting of an oval cover, A, with a ledge, B, and a shoulder, B', above it at the edge, as set forth.

2. The herein-described design for a dinner-dish, the same consisting of an oval dish, C, with a straight collar, D, at the upper edge, 45 and swelled out and downward on a gentle curve, and provided with a concave base, E, with a bead, F, as set forth.

3. The herein-described design for a handle for dinner-dishes, the same consisting of two 50 fluted rods, G, inclined toward each other, and united at their upper ends by a horizontal-like rod, the ends of these rods being ornamented with leaf ornamentation H, as set forth.

4. The herein-described design for a handle 55 for dinner-dishes, the same consisting of two fluted rods, G, inclined toward each other and united at the upper ends by a like fluted rod, the ends of these rods being ornamented by leaf ornamentation H, and the space between 60 the inclined rods filled in with a plate, K, having a recess, L, in its upper edge, as set forth.

ELIJAH CHETWYND.
